Patented Jan. 6, 1914.

UNITED STATES PATENT OFFICE.

OTTO ERNST, OF LARCHMONT, NEW YORK.

VALVE FOR INTERNAL-COMBUSTION ENGINES.

1,083,812.

Specification of Letters Patent.

Patented Jan. 6, 1914.

Application filed April 9, 1912. Serial No. 889,576.

To all whom it may concern:

Be it known that I, OTTO ERNST, a citizen of the United States, and a resident of Larchmont, in the county of Westchester and State of New York, have invented a new and Improved Valve for Internal-Combustion Engines, of which the following is a full, clear, and exact description.

My invention relates to a form of valve for internal combustion engines, and is preferably of the rotary type; and the object thereof is to provide an improved construction of this sort in which all of the defects inherent in rotary valves for gasoline motors are eliminated.

To this end I construct my improved valve with spindles that are so mounted as to have a certain degree of lateral play in the bearings which receive them, and I provide resilient means to hold the valve against its seat without opposing any appreciable friction to the movement of the same. This arrangement of parts allows for the necessary expansion of the valve in the operation of the motor without permitting leakage or in any way interfering with the efficiency of the working of the valve in practice.

Reference is to be had to the accompanying drawings forming a part of this specification, in which the same characters of reference indicate the same parts in both the views.

Figure 1 is a longitudinal sectional view, partly in elevation, showing the manner in which my valve is mounted in operative position in the framework of a four-cylinder motor; and Fig. 2 is a cross sectional view showing a casing for a pair of valves, one for controlling the supply of fuel to the cylinders and the other for controlling the exhaust of the same.

Referring particularly to the drawings the numeral 1 represents the framework of a four-cylinder motor that is preferably of the four-cycle type, and 2 are the cylinders thereof provided with the usual water jackets 3. These cylinders are each provided with inlet and outlet ports 4, shown as being formed on the tops thereof; but obviously I may form these ports in the sides of the cylinders near the tops, and make the valves extend along the sides near the tops accordingly. In the form shown in the drawings, however, these valves are mounted on the tops of the cylinders, and

extend from one cylinder of the row to the last one.

The edges of the ports 4 are elevated, forming seats 5, and 6 is a casing in which is mounted the valve body 7. This valve body is in the form of a hollow rotating cylinder having four pairs of ports 8, 9, 10 and 11 extending through its walls, the members of each pair of ports being located at diametrically opposite points, and the pairs of ports being spaced 90° apart around the circumference of the valve, and in such relative position as to make the first, second, fourth and third operate in succession in the order named.

The valve body is provided with spindles 12 extending from the ends thereof; and 13 represents a screw plug which closes one end of the valve casing. This bushing has a bearing opening 14, and a similar opening 14 is provided in the opposite end of the casing. These openings are of slightly greater diameter than the valve spindles 12, so as to give the valve body a certain amount of lateral play, and one of the spindles 12 projects beyond the adjacent end of the casing 6, and receives a driving gear 15, by means of which this valve is operated at one-fourth the speed of the crank shaft.

16 represents a removable plate for closing the top of the hollow valve casing 6; and 17 is a shoe extending longitudinally of the valve and provided with transversely-extending lugs 18 on the face adjacent the valves 7. These lugs are arranged in pairs, the pairs being located at suitable distances apart; and between the members of each pair of lugs 18 are rollers 19 mounted on spindles which enter suitable bearing openings in these lugs. These rollers bear upon the outer surface of the valve, but oppose no friction to the rotation thereof.

The shoe 17 has a number of recesses 20 in its opposite face, and these recesses receive the reduced ends 21 of a corresponding number of pins 22, and have screw-threaded engagement with the movable top 16 on the valve casing, and are held in place by means of lock nuts 23. The pins 22 are also provided with spiral springs 24 coiled around the same inside of the valve casing and bearing upon the shoe 17, the inner face of the plate 16 having suitable recesses to receive these springs.

The numeral 25 represents suitable wash-

ers between the ends of the valve body and the ends of the valve casing to prevent leakage; and 26 represents suitable fastening devices to hold the plate 16 in place. The 5 valve casing has a pair of openings in its sides, shown at 27 and 28, through which the fuel is supplied or the exhaust gases discharged, as the case may be.

According to my invention the same type 10 of valve is used for both the inlet and exhaust side of the engine, and the valve casing 6 will be provided with a longitudinal partition 29 to separate one valve from the other. In Fig. 2 only one valve is shown. 15 The valve is put in place through the open end of the casing before the plug 13 is screwed on, and the screw-threaded plug 13 is provided with a polygonal projection so that it can be screwed up to press the washers 25 snugly against the ends of the valve and prevent any leakage around the ends through the bearing openings 14.

The valve body 7 is held firmly against the seats 5 of the ports 4 by means of the 20 springs 24 pressing the shoe 17 against the opposite side of the valve, the valve moving laterally on account of the play afforded by the openings 14, into a snug-fitting position. These springs are of course made of 25 the proper strength to hold the valve to its seat at all times; but on account of the anti-friction rollers 19, the rotation of the valve is not in any way obstructed.

The manner of operation of my invention 30 will be apparent.

In the case of the inlet valve the gaseous fuel will be supplied to the inside of one-half of the valve casing and pass through the ports 8, 9, 10 and 11 to the interior of 40 the valve body. As fast as one of its ports comes into registry with one of the ports 4, this fuel will enter the corresponding cylinder, and as the valve rotates at one-fourth the engine speed, communication will be established between each cylinder and the source of fuel supply twice for every revolution of the valve. In the case of the exhaust valve the fuel will be discharged in a corresponding manner.

50 It will be seen that the springs 24 are located outside of the direct path of the incoming and outgoing gases. The degree of snugness with which the valve fits in place can be regulated by turning the screw plug 55 13; while the springs 24 will always hold the valve snugly against the seats 5, while at the same time allowing for expansion after the motor heats up in the course of its operation. Thus, the tendency of the valve 60 to stick is practically eliminated; and it will be noted that I obtain this result without increasing the friction or wear upon the valve.

My improved valve is thus capable of operating as long as other valves of this type

which do not embody the advantages herein set forth.

I wish to have it understood that the above description and accompanying drawings are illustrative only, setting forth but one embodiment of my invention; but I do not wish to be limited to the details thereof, except in so far as indicated in the accompanying claims, reserving to myself the right to vary the arrangement of the parts as far as is permitted by the scope and spirit of my invention.

Having thus described my invention, I claim as new and desire to secure by Letters Patent:

1. In an internal combustion engine, the combination of a valve casing, a rotary valve body located therein, spindles projecting therefrom and mounted in the walls of the casing, packing means carried by said spindles for the ends of the valve body, said casing having a screw-threaded opening at one end of said valve body, and an adjustable plug for said opening to cause the end walls of the casing to have snug engagement with the packing adjacent the ends of the valve body.

2. In an internal combustion engine, the combination of a valve casing, a rotary valve body mounted in said casing, said valve body having spindles projecting from its opposite ends, said spindles being mounted in the walls of the casing, said walls having bearings for said spindles of greater size than said spindles, to enable the valve to have side play for purposes of adjustment, and means for pressing said valve firmly to its seat.

3. In an internal combustion engine, the combination of a valve casing, a rotary valve body received therein, said casing having a port communicating with the power chamber, the edges of said port constituting seats for the valve, spindles projecting from the ends of said valve, said spindles being mounted in bearings in the walls of the valve casing, said bearings being of greater size than the spindles to allow the valve to move laterally for adjusting the same, and resilient means for forcing said valve body snugly against said seat.

4. In an internal combustion engine, the combination of a valve casing, a rotary valve body therein, means for mounting said valve body to enable the same to have side play for purposes of adjustment, the said casing having a port leading to a power chamber, the edges of said port constituting a seat for the valve body, a shoe carrying a plurality of anti-friction rollers engaging the outer face of said valve, and resilient means for pressing said rollers against the valve to force the same into snug engagement with said seat.

5. In an internal combustion engine, the

combination of a valve casing, a rotary valve received therein, said valve having means for mounting the same to allow it to have a certain amount of side play for adjusting the valve, said valve casing having a port leading to a working chamber, the edges of said port forming a seat for the valve, a shoe extending longitudinally of said valve and having transverse projections on the face of the same adjacent the valve, a plurality of anti-friction rollers carried by said shoe, the spindles of said rollers being supported by said projections, means extending through the wall of the valve casing and engaging said shoe to hold said shoe against movement, and resilient means mounted inside of said casing and engaging the shoe to press the same against the valve and force the valve body snugly against its seat.

6. In an internal combustion engine, a pressure shoe having a pair of transverse

projections extending from one face, each of said projections having a bearing opening, the said openings being arranged in longitudinal alignment, and an anti-friction roller having journals mounted in said bearing openings. 25

7. In an internal combustion engine, a pressure shoe having a plurality of pairs of transverse projections extending from one face, each of said projections having one or more bearing openings, the bearing openings of each pair being arranged in longitudinal alignment, and anti-friction rollers having 35 journals mounted in said bearing openings.

In testimony whereof I have signed my name to this specification in the presence of two subscribing witnesses.

OTTO ERNST.
